ELECTRIC WAVE GUIDE

Edward Cecil Cork and Michael Bowman-Manifold, Ealing, London, England, assignors to Electric & Musical Industries Limited, Hayes, England, a company of Great Britain

Application April 18, 1945, Serial No. 589,069
In Great Britain September 1, 1942

Section 1, Public Law 690, August 8, 1946
Patent expires September 1, 1962

7 Claims. (Cl. 178—44)

1

This invention relates to electric wave guides which are employed for transmitting electro-magnetic energy of very high frequency. The invention is exclusively concerned with the type of wave guide consisting of a hollow metallic conductor.

It has been found necessary to provide for the rotation of a section of a wave guide with respect to an adjacent section. For example, in a transmitting or receiving system where the energy transmitted or received is picked up by a wave guide it may be desired to associate with said wave guide a reflector for the transmitted or received energy and to cause the wave guide and the reflector to be rotated during transmission or reception. With such a construction it is desirable that the transmitter and receiver be located at a point remote from the transmitting or receiving portions of the wave guide and their associated reflectors and consequently the provision of means which enable one section of the wave guide to be rotated with respect to another section becomes necessary. It has been found impracticable for a variety of reasons to arrange the relatively rotatable sections of the wave guide in electrical contact with one another since in the first place such contacting sections will give rise to impedance variations at their points of contact and, furthermore, due to their frictional engagement they will give rise to the introduction of undesirable electrical noise.

It is therefore the object of the present invention to provide for the relative rotation of two sections of a wave guide without having the two sections in electrical contact and without the introduction of undesirable impedance changes and without permitting the escape of a substantial amount of energy.

According to the invention an electric wave guide is provided having two adjacent sections mounted for relative rotational movement, said sections having overlapping surfaces which are not in contact with one another, said overlapping surfaces having such dimensions as to afford an effective short circuit at the adjacent ends of the sections of the wave guide. The overlapping surfaces are air-spaced and since the two sections of the wave guide are not in contact with one another undesirable electrical noise such as referred to above is not produced and as stated by suitably choosing the dimensions of the overlapping surfaces an effective short-circuit is provided at adjacent ends of the sections so that no substantial impedance variation is produced at the adjacent ends of the sections and the escape of a substantial amount of energy is prevented.

2

In order that the said invention may be clearly understood and readily carried into effect various examples according to the invention will now be described with reference to the accompanying drawings in which:

Figure 1 shows a longitudinally sectional view through two sections of a wave guide constructed in accordance with the invention.

Figures 2, 3 and 4 are similar views illustrating modified forms of the invention and,

Figure 5 is a view of a transmitting and receiving apparatus embodying the construction shown in Figure 1.

Referring now to Figure 1 of the drawings, the reference numeral 6 indicates one section of a wave guide which comprises a hollow tubular conductor of circular form in cross section and which may be used for the transmission of waves, in particular waves of the E_{01} mode. The reference numeral 7 indicates a similar section of wave guide, the adjacent ends of the two sections being spaced apart as shown and provided with annular flanges 8 and 9, as shown. The flanges 8 and 9 provide the overlapping surfaces referred to above. In general, a wave transmitted past the gap between the adjacent ends 6 and 7 tends to radiate a small portion of its energy through the gap, and further, the gap presents an impedance to the longitudinal surface currents set up in the guide. In the construction shown in Figure 1 in order to maintain the impedance at a minimum and in order to prevent a substantial escape of energy via the gap, the distance between the two flanges is small and is constant, throughout the area of the flanges and the radial depth of the flanges is so chosen that it effectively provides a quarter wave-length line open-circuited at the end remote from the adjacent ends of the sections 6 and 7. A quarter-wavelength line open-circuited at one end effectively provides a short circuit at the opposite end and, consequently, in the construction shown in Figure 1 an effective short circuit is presented at the adjacent ends of the sections 6 and 7. Where, for example, the wave guide has a suitable diameter for the transmission of energy of a free space wave length of 3.2 centimeters, the distance apart of the flanges 8 and 9 may be half a millimetre and the flanges 50 may be approximately 8 millimetres in radial depth. With the construction shown one section can thus be rotated relatively to the other section and since there is no direct contact between the two sections the introduction of electrical noise as referred to above is avoided, and more-

over, a minimum impedance is introduced in the guide.

Figure 2 of the drawings illustrates a modified form of the invention in which the flanges 8 and 9 are composed of an odd integral number of quarter wavelength portions and are shaped to present a so-called labyrinth construction. The length of the portions of the labyrinth should be chosen so that the portions X and Y are approximately equal to a quarter-wavelength of the energy transmitted along the guide. Also in order that the arrangement should cause a minimum disturbance to the waves transmitted along the guide and in order to reduce the escape of energy to a minimum, the portions X should have a larger spacing than the portions Y so that a wave tending to escape suffers repeated reflections and is thus substantially attenuated due to the unequal characteristic impedances of the portions X and Y.

Figure 3 shows a further modification of the invention in which the flanges 8 and 9 are again composed of an odd integral number of quarter wavelength portions. In the example shown in Figure 3 the flanges are formed from three quarter wavelength portions and the distance between the two flanges at the central portion is not constant since the flange 9 is provided with an annular protrusion 10 which makes the characteristic impedance of the central portion different from that of the other portions so as to cause repeated reflection of a wave tending to escape.

It is not necessary that the overlapping surfaces afforded by the flanges 8 and 9 should lie, in general, in a plane transverse to the axis of the guide since the effect of the invention can be obtained if the overlapping surfaces are, in general, concentric with the axis of the guide.

Figure 4 of the drawings illustrates a construction of this latter form from which it will be observed that the section 6 is provided with an extension 11 of large diameter which receives the adjacent end of the section 7. In this case the length of the section 11 is chosen to be effectively equal to a quarter-wavelength of the energy transmitted along the guide.

Figure 5 of the drawings illustrates apparatus for transmitting and receiving high frequency energy with which the invention may be employed. In this apparatus a transmitting aerial 12 is employed which comprises a wave guide section having a slot 13 through which energy is radiated. The aerial 12 is disposed at the focus of a parabolic reflector 14 which causes the energy to be radiated in a desired direction. The receiving aerial 15 also comprises a wave guide section provided with a slot 16 which is disposed at the focus of a further parabolic reflector 17. The energy transmitted from the aerial 12 is fed thereto through a wave guide section 18 and the energy picked up by the receiving aerial 15 is fed therefrom to a wave guide section 19, the sections 18 and 19 being connected respectively to a transmitting and receiving apparatus located at a point remote from the aerials 12 and 15. It is desirable in operation of the apparatus shown in Figure 3 to rotate the reflectors 14 and 17 and their associated aerials relatively to the guide sections 18 and 19. For this purpose a suitable motor 20 is provided which is so coupled to the reflectors 14 and 17 and their associated aerials as to cause the latter to rotate relatively to the wave guide sections 18 and 19. To permit of the rotation of the wave guide sections forming the aerials 12 and 15 with respect to the stationary wave guide

sections 18 and 19, the adjacent ends of the sections 18 and 12 and 15 and 19 are provided with flanges in the manner shown in Figure 1, the adjacent ends of the wave guide sections being located in housings 21 and 22 respectively which serve to support the rotatable sections and also serve to afford water-tight glands. It will thus be appreciated that by the provision of the invention it is possible to effect rotation of the aerials 12 and 15 whilst permitting the transmitting and receiving apparatus to remain stationary and to be located at a point remote from the aerials and without introducing the disadvantages referred to above.

15 What we claim is:

1. An electric wave guide devoid of any inner conductor and having two adjacent sections mounted for relative rotational movement, said sections having annular flanges on the adjacent 20 ends thereof, at least one of said flanges having a raised annular surface portion connected to the body of the flange by substantially cylindrical surface portions, the radial width of said annular surface portion being effectively 25 equal to a quarter-wavelength of the energy to be transmitted along the guide and the spacing between said annular surface portion and the corresponding surface of the opposing flange being different than the spacing between the remaining 30 portions of the flanges to provide different characteristic impedances thereby to provide repeated reflection of the energy passing between said flanges.

2. A wave guide in the form of a number of 35 hollow conductive tubes arranged in a coaxial end-to-end relationship, said tubes being rotatable with respect to one another about their common axis, said tubes being provided with overlapping surfaces at their adjacent ends, said surfaces having a narrow gap therebetween, the extent of overlap of said surfaces being equal to an odd integral number of straight quarter wavelength portions, said straight portions being arranged to form a zig-zag passageway from the interior 45 of said tubes to ambient space, to provide series connected sections of said gap having different characteristic impedances so as to cause repeated reflection of energy which tends to escape through said gap.

50 3. A wave guide structure having two abutting coaxially arranged sections arranged for relative movement about the axis of said sections and complementary conductive flange members affixed to the adjacent ends of said sections, said conductive flange members having a plurality of annular surface portions located alternately in two planes and a plurality of cylindrical surface portions parallel to the axis of said structure interconnecting the annular surfaces, the radial dimensions of said annular surface portions and the heights of said cylindrical surface portions being substantially a quarter wavelength at the operating frequency, said cylindrical surface portions being spaced apart by a distance different 55 from that by which the annular surface portions are spaced.

4. In a hollow-pipe wave guide, two abutting coaxial sections one of which is rotated on a longitudinal axis while the other remains stationary, 60 and a conductive flange individual to each one of the abutting ends of said sections, said flanges being provided with complementary annular rib and channel surfaces, the axial and radial dimensions of said rib and channel surfaces being substantially 65 equal to a quarter of the operating

wavelength and the annular surfaces being spaced apart to a different degree than the cylindrical surfaces between said annular surfaces whereby an effective short circuit is formed between said sections.

5. A wave guide structure having two abutting sections coaxially arranged for relative rotational movement about the axis of said sections, and complementary conductive flange members arranged on adjacent ends of said abutting sections, said flange members having annular land and groove portions connected by cylindrical wall portions, the land portions of one flange nesting within the groove portions of the other, the widths of said land and groove and wall portions being substantially equal to a quarter wavelength of the energy transmitted along the guide, the spacing between said land and said groove portions being different than that between adjacent wall portions.

15 6. A hollow pipe wave guide comprising two sections having overlapping conductive flanges mounted on adjacent ends thereof, said two flanges being out of mutual contact and having telescoped annular groove and land portions connected by axially arranged cylindrical portions, said flanges being so dimensioned that each groove or land or cylindrical portion is approximately equal to a quarter-wavelength of the energy transmitted along the guide, the spacing between land and groove portions being greater than the spacing between cylindrical portions.

10 15

20

30

7. A hollow pipe wave guide having two sections having overlapping conductive flanges mounted on adjacent ends thereof, said two flanges being out of mutual contact and having in a plane passing radially through the axis of the guide a cross-section forming short straight gaps connected in series, the length of each of said gaps being approximately equal to a quarter-wavelength of the energy transmitted along the guide and the width of the gaps extending radially of said guide being greater than the width of the gaps extending axially thereof.
